Charles W. Harrold, Shaker Heights, and Clyde G. Horton, Bedford, Ohio, assignors to Harris-Seybold-Potter Company, Cleveland, Ohio, a corporation of Delaware

Application December 10, 1934, Serial No. 756,794

23 Claims. (CL. 101—247)

This invention relates to improvements in printing presses, and has to do with cylinder mounting with throw-off means for a printing couple and for an inking mechanism, and with the mounting of the inker.

One of the objects of the invention is the provision of novel means for mounting cylinders in printing presses.

Another of the objects of the invention is the provision of a simplified throw-off mechanism, by means of which a cylinder is moved transversely to its length, either manually or automatically, so as to separate it from one or more other cylinders of a printing couple.

Another object is the provision of apparatus of this character in which the cylinder rotates upon the shaft and in which the transverse movement of the shaft is brought about by a turning movement applied to one end of the shaft and transmitted through the shaft itself to the other end thereof.

Another object is the provision of apparatus of the character stated in which is embodied means for regulating the limits of the cylinder throw-off movement by manipulation of a single adjustment.

Another object is the provision of simple and improved inker throw-off mechanism which is adapted for either manual or automatic operation, together with means associated with the throw-off means for exposing the form rollers of the inker for repair or replacement without disturbing any other elements of the inker.

Other objects and features of novelty will appear as we proceed with the description of that embodiment of the invention which, for the purposes of the present application, we have illustrated in the accompanying drawings, in which

Fig. 1 is a side elevational view of an offset printing press embodying the invention;

Fig. 2 is an end elevation of the same with certain parts removed and others broken away in order to more clearly illustrate the invention;

Fig. 3 is a view similar to Fig. 1 after the trip mechanism has been actuated, showing the blanket cylinder thrown off and the form rollers of the inker thrown off;

Fig. 4 is a further fragmental side elevation, showing the principal part of the inker raised to expose the form rollers;

Fig. 5 is a fragmental plan view, partly in horizontal section, of the impression cylinder and the manual throw-off mechanism therefor;

Fig. 6 is a side elevation of the same with the mechanism in the throw-off position;

Fig. 7 is a vertical central sectional view of the blanket cylinder and its mounting;

Fig. 8 is a plan view, partly in section, illustrating the pivotally mounted inker frames;

Fig. 9 is a detail end elevation showing the eccentric sleeve mounting for one of the cylinder shafts and the adjustable key connection between the shaft and sleeve;

Fig. 10 is a detail sectional view taken substantially on the line 10—10 of Fig. 1;

Fig. 11 is a fragmental elevational view showing the free end of the lower inker frame in its raised position; and

Fig. 12 is a fragmental, longitudinal sectional view of a modified form of cylinder mounting.

It is common in printing presses to provide means for shifting one cylinder of a pair or couple transversely to space the contacting surfaces slightly in order to prevent offsetting whenever there is any interruption of the feed of paper sheets. Usually the cylinder is keyed to its shaft, and the latter is journaled in eccentric bearings or sliding box bearings in the frame members. Each of the two bearings is moved by a separate operating means, and the two such means are connected so as to operate simultaneously, thus moving the cylinder axis parallel to itself. If a change in the extreme positions of the cylinder is desired, as is necessary to vary the printing pressure or to allow for different thicknesses of paper, it is usual to alter the mechanism at both ends of the shaft, and considerable care must be taken to preserve the parallelism of the altered cylinder with the others of the couple.

In the embodiment of the invention herein illustrated, the movable cylinder comprises a shaft upon which the cylinder itself rotates, eccentric sleeves in which the shaft is mounted and to which it is preferably keyed, and an operating crank attached to one of the sleeves. Variation 40 of the limits of the cylinder throw is accomplished by a single length of adjustment in one of the operating links or levers.

Cylinder throw-off

Referring now to the drawings, the frame of the press comprises side members 10 and tie rods 11. In the printing couple illustrated, there are three parallel shafts 12, 13 and 14, upon which are rotatably mounted a plate cylinder 15, a blanket cylinder 16, and an impression cylinder 17.

The frame members 10 are formed with three sets of aligned bosses 18, 19 and 20. In the bosses 18 are mounted sleeves with concentric holes for the reception of the shaft 12. Roller 55

bearings 22 are mounted upon the shaft adjacent these sleeves, and the cylinder rotates upon these bearings. Inasmuch as the axis of this cylinder is fixed, it is not essential that the cylinder rotate upon the shaft. It could be keyed to the shaft, and the shaft could rotate in the sleeves in which it is journalled, but for the sake of uniformity, we prefer to have the cylinder rotate upon the shaft, as herein shown.

10 Within the bosses 19 are rotatably mounted sleeves 23 and 23' provided with eccentric bores for the reception of shaft 13, see particularly Fig. 7. The shaft is rigidly connected with sleeve 23 by a key 24, and the sleeve 23 is provided with an integral crank 25 by means of which it may be oscillated. Sleeve 23' is provided with a flange 26 which engages the outer surface of the frame. This flange is formed with a pair of arcuate slots 27 that receive studs 28 mounted in the frame. Washers 29 under the heads of the studs and preferably supported by spacing tubes engage the flange on the sides of the slots 27 and hold the sleeve 23' against movement outwardly away from the frame. In 25 the end of shaft 13 there is a diametrical slot which is covered by a cap plate 30, and in this slot there is a key 31 one end of which projects outwardly over the face of flange 26. The flange carries a pair of threaded ears 32 within which 30 are mounted adjusting screws 33. By this means the relative angular positions of the shaft 13 and the sleeve 23' may be adjusted within certain limits, which adjustment as a rule will be necessary only when the machine is being assembled. The cap plate 30 is held in position upon the shaft 13 by a pair of machine screws 135 which extend through smooth openings in the cap into threaded openings in the end of the shaft. At the opposite end of the shaft there 35 is a similar cap plate 136 which is also held in place by machine screws 135.

Upon the shaft 13 we mount the inner races of roller bearings 22, these races being spaced from the sleeves 23 and 23' by short sleeves 34 and 35, while the two races are spaced apart by a sleeve or tubular member 36. When the parts are in position, one or both pairs of screws 135 may be drawn up sufficiently to put the desired clamping pressure on the inner races 22 of the roller bearings. At one end of the cylinder overhanging the sleeve 34 there is a ring gear 37 which is bolted or otherwise secured to the cylinder.

On the end of the crank 25 there is mounted 55 a nodule pin 38 which is perforated to receive the threaded end of a short connecting rod 39, the lower end of which is formed with an eye which surrounds a pin 40 mounted in a bell crank lever 41 which is pivoted to the frame at 42. 60 This connecting rod 39 is provided with nuts on opposite sides of the nodule pin, whereby adjustments can be made. The lever 41 is provided with two adjustable studs 43 and 44 which are adapted to engage with stop blocks 45 and 46 respectively on the frame of the machine, thereby limiting the movement of the lever in either direction.

The righthand end of lever 41, as viewed in Figs. 1, 3 and 10, is formed with a slot 47 which 70 takes a pin 48 that is mounted in a lever 49 which pivots upon a pin 50 set into the frame 10. The lever 49 is also provided with two forwardly projecting pins 51 and 52. These latter pins are adapted to be engaged on their lower sides by shoulders on the opposite sides of a

plunger 53 which carries a roller follower on its lower end. This follower runs upon a cam 54 which is pinned to a shaft 55, the latter shaft carrying the delivery cylinder 56.

Pivots connected with the plunger 53 is a 5 trip rod 51, which may be automatically operated in connection with the sheet feeding mechanism of the press, or manually operated. It is shown in Fig. 1 in the normal running position. In order to guide the lower end of plunger 53, and in order to provide pressure to hold the plunger follower against the surface of cam 54, we mount the lower end of the plunger upon a pivot 58 carried by the bifurcated ends of a bell crank lever 59 which is pivotally mounted 10 upon the frame at 60. Within the bifurcated extremity of the other end of lever 59 we pivot a rod 61 which is slidably mounted in a perforated ear 62 projecting from the frame 10. A coil spring 63 surrounds the rod 61 between the 20 ear 62 and adjusting nuts 64 threadably mounted on the rod. Spring 63 therefore tends to lower pivot pin 58.

Now, assuming that the sheet feeding means is provided with an automatic trip mechanism, 25 then when there is an interruption to the feeding of sheets, the rod 51 moves toward the left from the position illustrated in Fig. 1, throwing the plunger 53 against the side of pin 51. As the high spot of cam 54 raises the plunger 53, 30 the shoulder on the left of the plunger engages beneath pin 51 and pushes it upward, thereby swinging the lever 49 from the position of Fig. 1 to that of Fig. 3. Lever 41 is thereby swung to the position of Fig. 3, pulling downwardly 35 upon the outer end of crank 25 and imparting a slight clockwise rotation to eccentric sleeve 23 which moves the shaft 13 sufficiently to throw cylinder 16 out of contact with cylinders 15 and 17. Cylinders 15 and 17 carry gears 65 and 66 40 respectively which mesh with gear 31. The throw-off of cylinder 16 is of course insufficient to disengage these gears, and hence the relative angular positions of the cylinders are maintained.

The mounting of the impression cylinder 17 is 45 the same as that of blanket cylinder 16. That is to say, it comprises a shaft 14 carried by eccentric sleeves 67 and 67' which are oscillatable in bosses 20, the shaft being keyed to both of these sleeves, and the cylinder being rotatable 50 upon anti-friction bearings 22 carried by the shaft.

Eccentric sleeve 67 carries a crank 68, upon the outer end of which is mounted a nodule pin 69. A connecting rod 70 extends through the hole in the nodule pin and its effective length may be varied by means of nuts 71 threaded upon the rod and engaging the nodule pin on opposite sides thereof. On its other end rod 70 is formed with an eye which receives a pin 72 set into one end of a hand lever 73 which is pivoted at 74 upon the machine frame. The hand lever 73 carries a projection in which is mounted a threaded stud 75 that is adapted to engage a stop 76 on the frame. Another stud 77 threaded into a projection 78 on the frame is adapted to engage crank 68 when the cylinder 17 is moved to throw-off position, and thus stops the movement in that direction.

When the hand lever 73 is in the position of Fig. 1, which is the normal running position, the cylinder 17 is in contact with the cylinder 16, that is, with the paper being printed interposed between them. When it is desired to throw off 75

Inker

the impression cylinder, the operator grasps the handle on lever 73 and raises it, thereby pulling connecting rod 70 toward the left until the crank 68 strikes the stud 77, which is the position of Fig. 6. By this movement the shaft 14 is rotated and moved eccentrically away from cylinder 16 and its shaft 13, separating the cylinders. The noddle pin 69 and the pivots 72 and 74 are so arranged that, in the operative position, pivot 72 lies just above the line of centers between pivot 74 and noddle pin 69. Printing pressure tending to separate the cylinders tends to throw the pivot pin 72 up still further, which is resisted by stop 76. Hence any accidental throw-off of cylinder 17 is avoided.

It will be obvious that the automatic or manual throw-off can be applied to any one of the three cylinders 15, 16 and 17, or to any two of them, or to all three, if desired, although the arrangement herein disclosed is preferred.

So far as we are aware, it is new in the art to employ a non-rotating shaft and to rotatably mount a cylinder upon such shaft. This arrangement results in certain important advantages, as follows: The cylinder may be removed from the press without disturbing the frame or necessitating split bearings for the shaft; the cylinder and shaft are less readily deformed by the passage of foreign objects between the cylinders, because a shaft rotatably mounted at only two points in the cylinder is more resilient than a shaft pressed into or integral with the cylinder; the shaft may be somewhat deformed without interfering with the printing operation, since the cylinder will continue to run true unless it also is deformed; this type of mounting permits the use of ball or roller bearings in conjunction with eccentric or otherwise movable bearings for the shaft without necessitating openings in the frame so large as to interfere with other parts of the machine.

Fig. 12 shows a modification of the construction illustrated in Fig. 7. The arrangement is similar to that of Fig. 7, but the eccentric sleeve 130 corresponding to sleeve 23 in Fig. 7 is provided with a cylindrical extension 131 concentric with the shaft 13 but spaced therefrom. The eccentric sleeve at the opposite end of the shaft is similarly formed. Surrounding the shaft 13 and extending nearly across the space between the frame members of the machine there is a sleeve 132 which at its ends has reduced portions 133 upon which are mounted the inner races of the roller bearings 22. These extensions 133 may also project into the spaces between the cylindrical extensions 131 and the shaft 13. The extensions 131 abut against the inner races of the bearings 22 and therefore hold them in position. The shaft 13 is keyed to the eccentric sleeve 130, and the operation of the throw-off is precisely the same as in the previously described form of the invention. This modification has certain advantages however. It provides greater rigidity by increasing the diameter of the cylinder supporting member between the bearings of the cylinder. Furthermore it permits removal of the cylinder without disturbing its bearings, by the withdrawal of the eccentric sleeve 130 and the corresponding sleeve at the opposite end of the mounting, and the withdrawal of the shaft 13, when the cylinder is free to be taken out of the machine without disturbing the bearings which remain on the sleeve 132, this sleeve being a trifle shorter than the distance between the bosses 19 on the frame.

The inker comprises a lower frame 80, which comprises two independent side members. This frame is pivotally mounted at one end upon a short shaft 81 which is fixed in an upwardly projecting part of the frame 10, and at the other upon a sleeve 82 mounted in the frame surrounding a short shaft 83, to which reference will be made again hereinafter. The two shafts 81 and 83 are, of course, in alignment. This frame 80 has brackets 84, 85 and 86 in which are rotatably mounted form rollers 87, 88 and 89 respectively, which run upon plate cylinder 15 in the normal printing position, as indicated in Fig. 1.

Also pivoted upon shaft 81 and sleeve 82 is a second or upper frame 90, having side members and cross struts. While the pivotal mounting of frames 80 and 90 about a common axis is the preferred construction, it is permissible to mount them upon separate axes, and one of them may be pivotally carried by the other, the latter being pivoted in the main frame of the machine. In frame 90 there may be mounted the remaining elements of the inker, including an ink fountain 91, an ink drum 92, storage rollers 93 and 93', and idler gears 94 and 95. A gear 96 on the inner end of shaft 83 meshes with idler 94 which drives a gear 97 on the shaft of roller 93, while idler 95 takes its driving force from gear 97 and transmits rotation to a gear 98 on the shaft of drum 92 and to a gear 99 on the shaft of roller 93'. In the operative position of the inker, the two storage rollers 93 and 93' transfer ink to the form rollers 87, 88 and 89 which spread it upon the plate cylinder 15.

The forward ends of the two side members of frame 80 are recessed to fit over upwardly projecting portions of the side members of the main frame 10. Within each of these side members are sockets receiving plungers 100 that are pressed upwardly by coil springs 101. The plungers engage the side members of the frame 80 and tend to raise that frame to the extent indicated in Figs. 3, 4 and 11. The forward ends of the side members of frame 90 rest upon the forward ends of frame 80 and hence are influenced by the springs 101 and their plungers 100.

We provide means, however, to pull down the forward ends of frame 90 against the action of springs 101 and to hold both frames in their lowered position, indicated in Fig. 1, this means serving further to raise upper frame 90 to its fully elevated position shown in Fig. 4. The means in question comprises a pair of connecting rods 102 adjustably pivoted to the forward ends of the side members of frame 90. The lower extremities of these connecting rods are curved and are pivotally connected at 103 with cranks 103' carried outside the main frame members by a rock shaft 104. On one end of this shaft there is pinned a hand crank 105 by means of which the shaft may be turned from one extreme position, illustrated in Fig. 1, through an intermediate position, illustrated in Fig. 3, where the springs 101 are free to act, and to its other extreme position, illustrated in Fig. 4, where the frame 90 is separated entirely from frame 80 and raised high enough to expose form rollers 87, 88 and 89 for removal and replacement. It will be noted that in Fig. 1 the pivot point 103 is over center in one direction, while in Fig. 4 it is over center in the other direction. Hence when either one of these positions has been assumed, the parts tend to remain in that position.

Adjustable screws 106 mounted in the connecting rods 102 engage the shaft 104 and limit the downward movement of rods 102 and the clockwise movement of crank 105. An adjustable screw 107 carried by the main frame 10 engages a projection 108 on the crank 105 and limits the upward travel of frame 90, as indicated in Fig. 4. It is desirable that the form rollers 87, 88 and 89 be lifted out of engagement with cylinder 15 whenever the feed of paper sheets is interrupted, and to this end we provide means for shifting crank 105 from the position of Fig. 1 to that of Fig. 3 whenever the throw-off for blanket cylinder 16 is operated. This means consists of a rod 109 pivoted upon the extremity of pivot pin 40 and resiliently supported from eccentric sleeve 23 by a coil spring 110. At its free end this rod is made slightly concave so as to fit upon projection 108 of crank 105. When the tripping mechanism of 20 the press operates to shift rod 57 toward the left from the position of Fig. 1, and the plunger 53 is raised by cam 54, moving levers 49 and 41 to the positions of Fig. 3, rod 109 is carried toward the left and swings lever 105 over dead center, 25 whereupon springs 101 exert pressure acting through plungers 100 to lift the forward extremities of frames 80 and 90, thereby raising the form rollers 87, 88 and 89 sufficiently to clear plate cylinder 15.

30 Driving connections

The power pulley of the machine is shown at 111. It is mounted upon a shaft 112 which carries a pinion 113 that meshes with a gear 114 on a short shaft 115. On the inner end of the 35 latter shaft there is keyed a gear 116 which meshes with gear 37 on blanket cylinder 16. The three cylinders of the printing couple are intergeared, as previously explained. When the blanket cylinder is thrown off, the movement is not 40 sufficient to throw gear 37 out of mesh with gear 116.

On shaft 115 outside of the frame 10 there is a sprocket wheel 117 over which runs a chain 118 that extends upwardly and over a sprocket 45 wheel 119 on shaft 83. It is by this means that the gear 96 is rotated and transmits driving force to the various moving parts of the inker, the connection of the latter with the gear 96 being unaffected by the swinging movement of frames 80 50 and 90, since the gear 96 is concentric with the pivots of these frames.

The dampening mechanism, which is indicated diagrammatically in the drawings, comprises a frame 120, a fountain roller 121, a swinging 55 ductor roller 122, a pair of rollers 123 and 124 in contact with the plate on the plate cylinder 15, and an intermediate roller 125. Roller 125 carries a gear which meshes with a gear mounted in frame 10 and indicated at 126, which in turn 60 meshes with a gear 127 on shaft 83. (See Figs. 2 and 8.)

Variations from the described structure may be employed. Accordingly, we desire it to be understood that the scope of the invention is to 65 be regarded as defined exclusively by the appended claims rather than by the foregoing description or the accompanying illustration.

Having thus described our invention, we claim:

1. In a machine of the class described, a frame, 70 a shaft journaled therein, a cylinder rotatably mounted on said shaft eccentrically with respect to the journals of the shaft, and means for displacing said cylinder transversely to its axis comprising means at one end of said shaft for im- 75 parting limited rotation thereto, said last men-

tioned means being adjustable for changing the limits of rotation of said shaft.

2. In a machine of the class described, a frame, a shaft mounted therein, a sleeve surrounding said shaft between frame members, a cylinder rotatably mounted on said sleeve, and means for moving said shaft parallel to itself in said frame, said shaft being removable longitudinally from the frame and sleeve, whereby the sleeve and cylinder 5 may be removed from the machine. 10

3. In a machine of the class described, a frame, a shaft mounted therein, a sleeve surrounding said shaft between frame members, a cylinder surrounding said sleeve, anti-friction bearings between said sleeve and cylinder, and means operable from one end of the shaft for moving the latter parallel to itself in said frame, said shaft being removable longitudinally from the frame and sleeve, whereby the sleeve and cylinder may be removed from the machine. 15

4. In a machine of the class described, spaced frame members, a shaft supported at its ends thereby, a cylinder carried by said shaft between the frame members, a member with which said cylinder cooperates, said cylinder being rotatably 25 mounted upon its shaft, means for rotating said cylinder, throw-off means comprising mechanism for moving said shaft toward and away from said cooperating member, said mechanism including the movable shaft itself, and means at one end 30 only of the movable shaft for changing the limits of movement of that shaft.

5. In a machine of the class described, a frame, a shaft, a cylinder rotatably mounted on said shaft, means for rotating said cylinder, throw-off 35 means comprising circular mountings for the ends of said shaft, said mountings being rotatable in the frame and being fixed to the shaft eccentrically, and said throw-off means also comprising means for turning one of said mountings. 40

6. In a machine of the class described, a frame, a shaft, a cylinder rotatably mounted on said shaft, means for rotating said cylinder, throw-off 45 means comprising circular mountings for the ends of said shaft, said mountings being rotatable in the frame and carrying the shaft eccentrically, said shaft being locked against rotation in one of said mountings, and said throw-off means also comprising means for turning said last-named mounting. 50

7. In a machine of the class described, a frame, a shaft, a cylinder rotatably mounted on said shaft, means for rotating said cylinder, throw-off 55 means comprising circular mountings for the ends of said shaft, said mountings being rotatable in the frame and carrying the shaft eccentrically, said shaft being fixedly keyed to one of said mountings and adjustably keyed to the other of said mountings, and said throw-off means also comprising means for turning one of said mountings. 60

8. In a machine of the class described, a frame, a shaft, a cylinder mounted upon and rotatable with respect to said shaft, means for rotating said cylinder, aligned eccentric sleeves rotatably 65 mounted in said frame and carrying said shaft, one of said sleeves having a crank by means of which it may be oscillated, and means for swinging said crank, said last named means being adjustable to vary the limits of movement of the 70 crank.

9. In a machine of the class described, a frame, a pair of aligned eccentric sleeves rotatably mounted in said frame, a shaft mounted in said sleeves, a cylinder rotatably mounted upon the 75

shaft between the sleeves, and means for moving said shaft transversely to itself comprising means for turning one of said sleeves, said shaft acting to transmit the turning motion to the other 5 sleeve.

10. In a machine of the class described, a frame, a shaft carried by the frame, a cylinder within the frame supported by and mounted to rotate around said shaft, anti-friction bearings 10 for the cylinder at the opposite ends thereof, annular abutments against which the inner ends of the inner races of said bearings engage, eccentric sleeves carried by the frame with openings therein for the reception of the ends of the shaft, 15 extensions for said sleeves projecting inwardly into engagement with the outer ends of the inner races of said bearings, and means for turning one of said sleeves.

11. In a machine of the class described, a 20 frame, a shaft carried by the frame, a cylinder within the frame supported by and mounted to rotate around said shaft, anti-friction bearings for the cylinder at the opposite ends thereof, annular abutments against which the inner ends 25 of the inner races of said bearings engage, eccentric sleeves carried by the frame with openings therein for the reception of the ends of the shaft, and clamping means carried by said shaft for forcing said eccentric sleeves inwardly to firmly 30 grip the inner races of said anti-friction bearings.

12. In a machine of the class described, a frame, a shaft carried by the frame, a cylinder within the frame supported by and mounted to rotate around said shaft, anti-friction bearings 35 for the cylinder at the opposite ends thereof, annular abutments against which the inner ends of the inner races of said bearings engage, sleeves movably mounted in the frame within which the ends of the shaft are supported, extensions for 40 said sleeves projecting inwardly into engagement with the outer ends of the inner races of said bearings, and clamping means carried by said shaft outside of the frame members for forcing said sleeve inwardly to firmly grip the inner races 45 of said anti-friction bearings.

13. In a machine of the class described, a hollow roll, an axle extending therethrough, bearings for said roll mounted on said axle, frame members, mounting blocks in said frame members, 50 said axle extending into said mounting blocks, caps over the ends of said mounting blocks, and screws extending through said caps into the ends of said axle.

14. In a machine of the class described, a 55 frame, mounting blocks in said frame, an axle supported in said mounting blocks, annular abutments carried by said axle, a roll mounted for rotation on said axle, anti-friction bearings interposed between said roll and said axle, and means 60 including said mounting blocks for clamping the inner races of said bearings against said abutments.

15. In a printing press, spaced frame members, 65 a hollow cylinder disposed between said frame members, an axle extending through said cylinder, roller bearings interposed between said cylinder and the axle, annular abutments carried by the axle against which the inner races of said 70 bearings abut, mounting blocks in said frame members for receiving and supporting the ends of said axle, caps on the ends of said mounting blocks, and screws extending through said caps into said axle.

16. In a machine of the class described, a 75

frame, elongate normally stationary means carried by the frame, a printing cylinder within the frame supported by and mounted to rotate around said means, and a pair of anti-friction bearings interposed between the cylinder and said 5 means, said stationary means comprising a hollow member having annular abutments against which the inner races of said bearings abut, and comprising also means for holding said races against said abutments including a removable 10 shaft extending through said bearings and said hollow member.

17. In a machine of the class described, a frame, elongate normally stationary means carried by the frame, a printing cylinder within 15 the frame supported by and mounted to rotate around said means, and a pair of anti-friction bearings interposed between the cylinder and said means, said means comprising the following elements, namely, a shaft extending through the 20 cylinder and longitudinally removable therefrom, a sleeve surrounding said shaft and having a portion against which the inner race of one of said bearings abuts, means for holding said inner race against said sleeve portion, and means cooperating 25 with said shaft and said holding means to prevent lateral movement of said sleeve relative to said shaft.

18. In a machine of the class described, frame 30 members, elongate normally stationary means carried by the frame members, a printing cylinder between the frame members supported by and mounted to rotate around said means, and a pair of anti-friction bearings interposed between 35 said cylinder and said means, said means comprising a sleeve in the cylinder having annular abutments for spacing the inner races of said bearings, mounting blocks in the frame members, a shaft extending through said sleeve and into 40 said mounting blocks, and clamping means carried by said shaft for forcing said mounting blocks inwardly against said inner races.

19. In a machine of the class described, a normally rotating printing cylinder, and elongate normally stationary means extending through the 45 cylinder for supporting the latter, said means comprising a plurality of hollow members upon certain of which the cylinder is mounted to rotate, a shaft through said hollow members, and means cooperating with said shaft for pressing 50 said hollow members against each other endwise, whereby they may be held in fixed relation to said shaft.

20. In a machine of the class described, a 55 frame, a carrier having ends rotatably journaled in said frame, a cylinder rotatably mounted on said carrier eccentrically with respect to the journals of the carrier and within the frame, a link and lever at one end of said carrier for imparting limited rotation thereto and so arranged 60 that the cylinder is in operative position when said link and lever are in substantial alignment, and means for changing the effective length of said link and lever for altering the operative position of said cylinder while maintaining said substantial alignment.

21. In a machine of the class described, a frame, a cylinder, a carrier for said cylinder extending therethrough, said carrier comprising 70 circular mounting blocks oscillatably supported in said frame and a shaft mounted in and keyed to both of said blocks, one of said key connections being adjustable, said cylinder being rotatably mounted on the carrier between said mounting 75

blocks on bearings arranged eccentrically with respect to the mounting blocks, and means for oscillating said carrier.

22. In a machine of the class described, a frame, elongate normally stationary means carried by the frame, a printing cylinder within the frame supported by and mounted to rotate around said means, and a pair of anti-friction bearings interposed between the cylinder and said means, 10 said means comprising the following elements, namely, a shaft extending through the cylinder and longitudinally removable therefrom, a sleeve within the cylinder and surrounding said shaft of such length as to be removable transversely from 15 the frame while remaining in the cylinder, said sleeve having a portion against which the inner race of one of said bearings abuts, means for holding said inner race against said sleeve por-

tion, and means effective to prevent lateral movement of said sleeve relative to said shaft.

23. In a machine of the class described, a frame, a normally rotating printing cylinder therein, and normally stationary means carried by the frame and extending through the cylinder for supporting the latter, said means comprising hollow means upon which the cylinder is mounted to rotate, a shaft through said hollow means and removable therefrom endwise by relative movement in one direction whereby the shaft may be removed from the cylinder while said hollow means remains therein, and other hollow means around the shaft for holding said first named hollow means in fixed lateral relation to said frame. 5 10 15
